DEWAXING MINERAL OILS

Roy N. Giles, Casper, Wyo., assignor to Standard Oil Company, Chicago, Ill., a corporation of Indiana

Application August 31, 1931. Serial No. 560,361

21 Claims. (Cl. 196—18)

This invention relates to the separation of wax from mineral oils and it pertains more particularly to a means for dewaxing lubricating oils so that they will have low pour points, or in other words, so that they will flow freely at low temperatures.

In the dewaxing process it is common practice to dilute the wax-bearing oil with "filter naphtha," chill the mixture to low temperatures for throwing the wax out of solution, and separate the wax from the diluted oil by filtering, settling or centrifuging. Some waxes, usually those of the so-called paraffin distillate range, contain relatively low melting point waxes which on cooling form well defined crystals that may be filtered or sweated for the removal of oil therefrom. Other waxes, called ceresins, are usually present in heavy motor base stock; the ceresins are usually of relatively high melting point, and they separate out from filter naphtha in a flocculent form so that filtration and/or sweating is impossible. Between the paraffin distillate and the motor base stock there are slop wax cuts which contain mixtures of paraffins and ceresins, and it has been practically impossible to separate these slop waxes from the oil because the amorphous structure prevents filtration, and because the crystalline structure and specific gravity may prevent effective sedimentation or settling. An object of my invention is to provide an improved process for separating waxes of this type from oil.

A further object is to provide an improved diluent for dewaxing processes. A further object is to provide a process for crystallizing the wax in such a manner that the crystals may be effectively filtered or settled without the use of settling agents or filter aids. A further object is to provide a finished oil of better color because of the lower reducing temperature made possible by the use of my improved diluent. A further object is to increase chilling rates and filter rates in a dewaxing process. A further object is to provide a cheaper, simpler and more effective dewaxing process as hereinafter described.

I have discovered that liquefied butane has remarkable new and unexpected properties as a wax diluent. Ceresins may be crystallized from liquid butane in a form which will permit rapid and efficient filtration. Mixtures of paraffins and ceresins may likewise be crystallized so that they may be either filtered or settled. A feature of the use of liquid butane is the complete solution of the wax before the chilling is begun, and to accomplish this solution I heat the waxy oil with liquid butane at a temperature of about

140° F. and at a pressure of about 110 lbs. per sq. in. The refrigeration may be accomplished by conventional means or it may be very rapidly brought about by the vaporization of a portion of the butane. I have discovered that the mixture may be chilled from 35° to 350° F. per hour and that the crystals formed by this rapid chilling can be readily filtered even though the wax mixture contains large amounts of ceresin wax.

My invention will be more clearly understood from the following description and from the accompanying drawing wherein I have diagrammatically illustrated a dewaxing plant in accordance with my invention.

The oil to be dewaxed may be a heavy petroleum distillate or steam refined residue, it being understood, of course, that different amounts of diluent will be used for oils of various compositions, viscosities, etc. In my preferred example I will describe the dewaxing of a heavy lubricating oil which is commonly known as a motor base stock. This oil may be produced from Mid Continent or any other crude petroleum, and it preferably has a flash point of about 470° F. and a viscosity at 210° F. of about 70—75 seconds Saybolt. The motor base stock may be a residual treated steam refined oil or it may be an overhead lubricating stock; the invention is particularly applicable to the latter case because overhead lubricants of this type cannot be readily dewaxed by other methods.

In practicing my invention I utilize a closed system, parts of which are adapted to withstand pressures upwards of 150 lbs. This is necessary because I use a diluent which is gaseous at normal temperatures and pressures, and particularly at the temperatures to which it must be heated for effecting complete solution. As a diluent I use liquid butane, which may be pure butane or which may be a mixture of butane with isobutane and/or small amounts of propane, pentane, etc. This mixture is usually defined by its vapor pressure, which in this case is about 20—50 lbs./sq. in. at 70° F. and 50—150 lbs./sq. in. at 130° F. Preferably its vapor pressure is 33 lbs. per sq. in. at 70° F. and 110 lbs. per sq. in. at 130° F.

Liquid butane from pressure storage tank 10 is discharged through pipe 11 and regulating valve 12 into heater 13 and thence through pipe 14 into mixer 15. Wax-bearing oil is introduced into the system by pipe 16 in amounts regulated by valve 17; it may be introduced directly into the mixer or it may be introduced into the butane line 14. It is important that the wax be completely dissolved in the liquid butane before the chilling is

initiated, and I have found that the mixture must be heated to a temperature of about 140 to 145° F. for effecting complete solution. If this step is omitted the crystal structure of the precipitated wax may be of entirely unsatisfactory nature; it may be impossible to filter the same, and if filterable, the filtrate may be cloudy and the filter cake may contain a large amount of oil.

After the mixture of butane and waxy oil has been heated and mixed to effect solution, the mixture is conducted by pipe 18 to cooler 19 which may be a heat exchanger or any other conventional apparatus for reducing the mixture to normal temperatures. From cooler 19 the mixture is conveyed through pipe 20 and reducing valve 21 to refrigerating or chilling chamber 22.

The refrigeration may be accomplished in any conventional manner; for instance, brine may be cooled in refrigerating plant 23 and circulated to 28 and from the chilling chamber by pipes 24. I may, however, effect refrigeration by vaporizing a part of the butane and withdrawing butane vapors through pipe 25. The butane light hydrocarbon mixture to be evaporated for effecting refrigeration may be introduced directly into the refrigerating chamber 22 by means of pipe 20A.

Heretofore it has been deemed necessary to refrigerate or chill the oil-wax mixture at a slow even rate for obtaining desirable wax crystal structure. I have discovered that when butane is used as a diluent the cooling rate may be increased from 35 to 350° F. per hour and that this high cooling rate produces crystals which can be readily filtered.

35 The mixture of diluted oil and wax crystals is removed from the bottom of refrigerating or chilling chamber 22, through pipe 26 and valve 27 and it is then introduced into wax filter 28. This filter may be of any desirable type and, per 40 se, it forms no part of my present invention, so that detailed description is unnecessary. However, a closed type pressure filter is desirable. The wax from the filter is removed by pipe 29 to suitable apparatus for re-melting it and recovering 45 the butane.

The diluted oil is discharged from the filter through pipe 30 into a sump 31 from which it is conveyed by pipe 32, pump 33 and pipe 34 to exchanger 35. In exchanger 35 I may heat the 50 mixture to a sufficiently high temperature to effect practically complete vaporization of the diluent at the pressure of the storage tank which may be about 150 lbs. per sq. in. I may use a lower storage pressure, however, and force the butane into 55 mixer 15 by means of a suitable pump (not shown), and in this case the mixture may be heated to a somewhat lower temperature. The temperature will be somewhat dependent on the proportion of diluent present, but it will be in the 60 range of about 350 to 450° F.

From exchanger 35 the gases and vapors are introduced by pipe 36 into flash drum 37, the butane vapors being discharged at the top of the drum through pipe 38, liquefied in condenser 39 and returned by pipe 40 to the butane storage tank 10.

Hot oil from flash drum 37 is drawn from the base thereof through pipe 41 and reducing valve 42. It is then flashed in low pressure flash drum 43. The heat contained in the liquid is usually sufficient to drive off the last traces of diluent, and to leave the oil with a sufficiently high flash point, but if desired additional heat may be introduced by means of coil 44. The finished oil is withdrawn through pipe 45, and the butane vapors

are withdrawn through pipe 46, compressed by pump 47, and forced through pipe 48 to condenser 49, wherein they are liquefied, the liquid butane being introduced into storage tank 10.

As hereinabove stated, the refrigeration step 80 may be accomplished by the vaporization of a portion of the diluent, in which case, enough extra diluent should be added so that after refrigeration the proportion will be about 70 to 80 parts of diluent to 20 or 30 parts of oil. Filtration has been effected with as high as 40% oil, but I found it more desirable to use the proportions above stated. The amount of butane or hydrocarbon mixture necessary for effecting refrigeration may be calculated for any given instance, and it may depend somewhat on the degree of insulation of the equipment. Roughly speaking, I use about one-half lb. of butane to 90 lower the temperature of 100 lbs. of liquid 1° F.

The butane vapors from refrigerator chamber 95 22 are withdrawn through pipe 25 and valve 51 by means of pump 47, and condensed and returned to storage together with butane vapors from low pressure flash drum 43. It should be understood, however, that any other suitable means may be 100 employed for handling the refrigerant liquids and vapors.

I want to emphasize the importance of liquid butane on the crystal structure of the wax which is precipitated therein. It has been assumed 105 that ceresin wax was amorphous, but in butane it not only shows a crystalline structure, but it shows crystals which are readily filterable, which is an innovation in this art.

I have found that the wax may be separated 110 from the oil by cold settling instead of by filtering, even though substantial amounts of paraffin wax are present. This is apparently due to the extremely low specific gravity and low viscosity of liquid butane. Its A. P. I. gravity is from 108 to 115 120, preferably about 114, and it weighs only 4.6 to 4.9, preferably 4.8 lbs. per gallon. The relative effectiveness of butane and filter naphtha as a settling agent is shown in the following table, wherein the last column is the difference in the 120 density between the wax and solution divided by absolute viscosity.

Filter naphtha diluent

Diluent ratio	Sp. gr. -10/60° F.	Saybolt vis. at -10° F.	Absolute viscosity at -10° F.	Relative settling tendency	125
25% oil 75% diluent}	.8280	45.1	.0719	1.64	130
15% oil 85% diluent}	.8127	37.0	.0402	3.32	
10% oil 90% diluent}	.805	35.5	.0337	4.18	

Butane diluent

25% oil 75% diluent	.7001	31.5	.0176	13.96
15% oil 85% diluent	.6670	29.8	.0082	33.61
10% oil 90% diluent	.650	29.1	.0034	87.10
				140

From the above table it will be seen that butane is about ten times as effective as filter naphtha in operations of this kind.

Another way of bringing out the remarkable 145 effectiveness of butane is to compare solvents which have equal settling tendencies. I have found that 4.5 parts oil in 95.5 parts filter naphtha is equivalent in this respect to 38 parts oil in 62 parts butane.

The effect of butane in decreasing the settling time will be apparent from the following table:

6	Solution	Appearance of wax	Settling tendency	Time before bright oil can be drawn
10	8.7% oil 90.3% filter naphtha}	Very flocculent	4.7	45 hours
	9.2% oil 90.8% filter naphtha}	Very flocculent	4.5	26 hours*
	8.7% oil 91.3% filter naphtha}	Fine crystals	97.0	4.5 hours
	8.7% oil 93.3% butane}	Fine crystals	95.0	6.5 hours
15	9.3% oil 90.6% butane}	Fine crystals	95.0	6.5 hours

*(This solution showed no tendency to settle within a reasonable time so some of the oil was filtered.)

The primary object of the dewaxing operation is to produce a motor oil having a low cold test. The cold tests produced by solutions 1 and 2 in the above table were 60° F. and 55° F. respectively, while solutions 3 and 4 (using butane) showed cold tests of 38° F. and 34° F. respectively. The word "oil" in the tables refers to the wax-bearing oil or motor base stock hereinabove described. These tables show the remarkable and unexpected superiority of butane as a diluent for dewaxing.

The low specific gravity and the low coefficient of viscosity helps to increase filter rates for the same reason that it helps to increase settling rates; in both cases the particular crystal formation, together with the characteristic properties (particularly low viscosity) of the diluent, combine to produce the desired result. In many instances I found that unless the waxy oil is heated with the liquid butane to effect complete solution the desired crystallization does not take place, and in that case the wax cannot be readily filtered or settled.

I have found that chilling rates may be obtained of an entirely different order from those heretofore employed in the refrigeration of oil-wax mixtures. Instead of limiting refrigeration to 4 or 5° per hour, I speed it up to from 35 to 350° per hour, preferably 150° F. per hour, and even at this high rate I have found that crystals are produced which may be readily filtered from or settled in the butane diluent.

While I have described in detail a preferred embodiment of my invention, it is understood that I do not limit myself to the details herein set forth, except as defined by the following claims, which should be construed as broadly as the prior art will permit. The term "butane" in these claims refers to a liquefied hydrocarbon having approximately the vapor pressure of normal butane, and therefore this expression shall include mixtures of butane with isobutane, pentane, propane, etc.

I claim:

1. The method of removing wax from a wax-bearing oil which comprises heating said wax-bearing oil with butane to effect complete solution of oil and wax therein, refrigerating the solution to cause crystallization of the wax, and mechanically separating said wax from said butane-oil mixture.

2. The combination of claim 1 wherein the temperature of heating is about 140° F., the butane being maintained under pressure to keep it in the liquid state.

3. The combination of claim 1 wherein the refrigeration is effected by the evaporation of a part of the diluent.

75 4. The method of obtaining filterable wax crys-

tals which comprises dissolving wax in liquid butane and chilling the solution.

5. The combination of claim 4 wherein the rate of chilling is from 35 to 350° F. per hour.

6. The method of removing paraffin-ceresin wax mixtures from oil which comprises dissolving said wax mixture in liquid butane, and rapidly chilling the mixture to about -20° F.

7. The method of removing wax from oil which comprises mixing about 3 or 4 parts of butane in the liquefied state with one part of a waxy oil at a temperature high enough to effect solution of the wax in the butane, cooling said mixture to about -20° F. to effect crystallization of the wax, and mechanically separating the wax crystals from the butane-oil mixture.

8. The method of dewaxing petroleum oils which comprises mixing liquid butane with waxy oil at a temperature of about 140° F. to effect complete solution of the wax in the butane, cooling the mixture and refrigerating it to a temperature of about -20° F. to effect crystallization of the wax, mechanically separating the wax crystals from the butane-oil mixture, removing the butane from the oil, and returning the butane to the system.

9. The method of dewaxing petroleum oils which comprises dissolving said oils in enough liquid butane to effect refrigeration by direct evaporation, and to leave about 7 parts of butane to 3 parts of oil and wax, chilling the mixture to about -20° F. by withdrawing butane vapors therefrom, compressing said butane vapors, liquefying them and returning them to the system, separating the wax from the oil-butane mixture, separating the butane from the oil, and returning said butane to the system.

10. The method of removing wax from a wax-bearing oil which comprises heating said wax-bearing oil with a normally gaseous hydrocarbon to an elevated temperature sufficient to effect complete solution of both oil and wax therein, refrigerating the solution to cause crystallization of the wax from the diluted oil in filterable form, mechanically separating said wax from said diluted oil, and separating the remaining diluent from the diluted oil.

11. The method of removing wax from a wax-bearing oil, which comprises mixing said oil with a normally gaseous diluent, chilling the mixture by vaporizing at least a portion of the diluent and effecting the chilling at a rate of about 150° F. per hour to cause crystallization of wax, and mechanically separating diluted oil from wax which is crystallized by the rapid chilling step.

12. The method of separating wax from oil which comprises mixing said oil with a normally gaseous hydrocarbon diluent, vaporizing at least a part of said diluent to effect refrigeration at a rate of about 35° to 350° F. per hour and to a temperature to cause the crystallization of wax in a readily filterable form, and mechanically separating the crystallized wax from the diluted oil.

13. In a process of dewaxing hydrocarbon lubricating oils the steps which comprise adding sufficient liquid butane to said oil under pressure to both reduce its viscosity to permit ready separation of wax at dewaxing temperatures, and to provide the necessary refrigeration to bring the mixture to such temperature, reducing the pressure on said mixture to reduce the temperature by evaporation of butane to precipitate the wax, mechanically removing the wax, and recovering butane from the dewaxed oil.

14. The process of separating hydrocarbon lu-

- bricating oil and wax occurring naturally there-
with which comprises heating said oil-wax mix-
ture with a normally gaseous, hydrocarbon re-
frigerant to an elevated temperature sufficient
5 to effect complete solution of both wax and oil,
effecting the major portion of the refrigeration
necessary to precipitate the wax by evaporation
of a portion of the hydrocarbon refrigerant there-
by precipitating said wax, separating said precip-
itated wax, and recovering dewaxed lubricating
10 oil from the remaining mixture.
15. The process of separating wax from oil
which comprises mixing with an oil-wax mixture
a liquefied normally gaseous hydrocarbon, main-
taining the mixture at elevated temperature and
15 at an elevated pressure sufficient to effect com-
plete solution of both wax and oil in the liquefied
hydrocarbon, cooling the mixture to effect solidi-
fication of wax in separable form from the solution
20 of oil in liquefied normally gaseous hydro-
carbon, retaining at least a portion of the liquefied
normally gaseous hydrocarbon in the oil to serve
as a diluent therefor, and separating the
solidified wax from the diluted oil.
25. The process of separating wax mixtures
from heavy lubricating oil stock containing the
same which comprises dissolving one volume of
said stock in at least two and one-half volumes
30 of a liquefied normally gaseous hydrocarbon di-
luent at an elevated temperature and pressure,
chilling the mixture to dewaxing temperature at
a rate of about 35° to 350° per hour, mechani-
cally removing the solidified wax from the oil-di-
luent solution, and removing the diluent from the
35 oil.
17. The process of claim 16 wherein liquefied
normally gaseous hydrocarbon diluent is first
separated from the oil at superatmospheric pres-
sure so that the removed vapors may be condensed
without being compressed and wherein the oil
from the superatmospheric separator is passed
to a low pressure zone for the final removal of
diluent from the oil. 80
18. The process of claim 16 wherein at least
a part of the refrigeration is effected by the di-
rect vaporization of a portion of the liquefied nor-
mally gaseous hydrocarbon from the diluted oil-
wax mixture. 85
19. The process of claim 16 wherein at least
a part of the cooling is effected by removing dil-
uent vapors from the diluted oil-wax mixture
to effect refrigeration by vaporization, and where-
in the removed diluent vapors are liquefied,
90 cooled, and re-introduced into the diluted oil-
wax mixture.
20. The process of claim 16 wherein liquefied
normally gaseous hydrocarbon diluent is intro-
duced into the diluted oil-wax slurry at a point
near the bottom of a body of said slurry. 95
21. The process of separating wax mixture
from heavy lubricating oil stock containing the
same which comprises dissolving one volume of
said stock in from two and one-half to twelve
100 volumes of a liquefied normally gaseous hydro-
carbon diluent at a temperature of about 140° F.
and a pressure of at least 110 pounds per square
inch, releasing the pressure on the system where-
by the diluent is allowed to vaporize, removing
105 said vapors at a rate to effect chilling at a rate
of from 35° to 350° per hour, leaving at least
about two and one-half parts of diluent per part
of oil in the cooled slurry for facilitating wax
separation, mechanically removing solidified wax
110 from the diluted oil, removing diluent from the
diluted oil by heating it at superatmospheric pres-
sure, and finally removing the last traces of dilu-
ent at a lower pressure. 115
